Des. 178,511
Patented Aug. 14, 1956

178,511

POWER LAWN MOWER

Walter B. Ford, Grosse Pointe, Mich., assignor to Detroit Harvester Company, Detroit, Mich., a corporation of Michigan

Application January 7, 1955, Serial No. 33,866

Term of patent 14 years

(Cl. D40—1)

Fig. 1 is a perspective view of a power lawn mower viewed from the front and right-hand side, showing my new design;

Fig. 2 is a similar perspective view viewed from the front and left-hand side;

Fig. 3 is a top plan view thereof;

Fig. 4 is a detail elevational view of the front of the mower; and

Fig. 5 is an elevational view of the mower from the rear.

The characteristic features of my design reside in the solid line portion.

I claim:

The ornamental design for a power lawn mower, substantially as shown and described.
